UNITED STATES PATENT OFFICE.

This patent was issued to Gustave A. Schreier, of Auburn, Illinois.

ELECTRICAL CONNECTOR.

No. 909,030.

Specification of Letters Patent.

Patented Jan. 6, 1909.

Application filed February 18, 1907. Serial No. 357,762.

To all whom it may concern:

Be it known that I, GUSTAVE A. SCHREIER, a citizen of the United States of America, and a resident of Auburn, county of Sangamon, and State of Illinois, have invented 5 certain new and useful Improvements in Electrical Connectors, of which the following is a specification.

My invention relates to improvements in 10 electrical connectors, and has for its object the provision of means for most readily establishing and breaking an electrical circuit, under the conditions of use herein-after detailed.

More particularly, my invention is 15 primarily designed for use in connection with flexible conductors for mining motors adapted for employment when the train is entering a room or passage of the mine into 20 which the trolley conductor does not extend.

It is frequently found necessary in practice to employ a flexible conductor in connection with reel-mechanism for conveying 25 current to the motor when entering rooms or passages little used, those newly constructed or where the rails have not been bonded or are formed of wooden stringers.

The common practice has been to hook 30 one terminal of a flexible conductor over the trolley, and adjust the other terminal in contact with the bonded rail to establish circuit with the motor as it proceeds beyond the trolley conductor. This involves not a little delay, since the motor must be stopped 35 until connection is made or broken.

Accordingly, I have devised means, useful 40 under other conditions as well, whereby the end of the flexible conductor may be instantly connected with a suitable terminal socket, and will be automatically disconnected 45 therefrom upon the return of the motor. This improvement contemplates the use of a socket suitably constructed to admit of immediate connection and automatic disconnection, positioned at the entrance of 50 each room or passage, wherein it is desired that the motor shall proceed beyond the trolley of third rail conductor. At the end of the flexible conductor normally wound 55 upon a reel, but adapted automatically to be paid out or rewound, is a suitable connector-member for co-acting with any of the several fixed sockets.

The foregoing reference to mining-motors 55 is made merely for the purpose of better explaining the utility of my invention, and

the conditions under which it is designed for use, but the structural features, which I shall now describe as to my improvements, are set forth in the annexed drawings and 60 claims.

Figure 1 of said drawings represents in plan view a socket with the terminal connector inserted therein. Fig. 2 is a view thereof in side elevation. Fig. 3 is a vertical section through these associated parts. Fig. 4 is a plan view of one of the connection sockets, and, Fig. 5 is a similar view of the terminal-connector with its top removed.

Throughout each of the several figures of 70 the drawings, I have employed the same character of reference to indicate similar parts.

Preferably a connection socket or member, as shown in Fig. 4, is positioned upon 75 a post, or other supporting structure, convenient to the entrance of each of the rooms or passages to be entered by the motor.

The device comprises a base plate *a* of 80 fiber or suitable insulating material, to which the positive and negative line-conductors *+* — respectively extended. The former is connected with a pin *b* protected by a partially surrounding plate *a'* of insulating material which also serves as a recessed 85 abutment, while the latter conductor is connected with the flanged socket-member *c* shaped from sheet metal, as shown. This socket-member comprises an integral stamping having forwardly positioned ears *c'*, and 90 rearwardly positioned flanges *c''* equipped with over-turned lips, as shown.

Referring to Figs. 1 and 5, the details 95 of the terminal connector adapted to be used in association with the above-described socket or stationary connector block, will now be explained. The body of said terminal, to which the flexible conductor *d* is connected, is formed of two separable blocks *e* *e'* of insulating material, preferably of 100 hard fiber, carrying a forwardly positioned nose *f* formed of metal with lateral projections or pins *f'*, extending therefrom. This metal part is connected with one of the strands of the flexible conductor, while the 105 other strand of said conductor is connected with the interior pin-socket *g*. The details of this construction will be more readily gathered by making reference to Fig. 5 of the drawings, showing an upper or covering 110 block *e* removed to expose the recessed base *e'* containing the respective terminal parts.

The pin-socket may be longitudinally slit for insuring better engagement with the co-acting pin *b*.

Assuming that the terminal connector is attached at the end of a flexible two-strand conductor conveying current to a traveling motor, it will be seen that the connection may be made with any of the terminal blocks or sockets of Fig. 4, wherever positioned along the track or a switch, simply by inserting said terminal connector in the manner shown in Figs. 1 to 3.

Some of the utilities of my invention may now be briefly referred to; principal of which is the employment thereof in mines. It will readily be seen, however, that the device is one well adapted for use in connection with any electrical appliance, wherein strain upon the conductor is to be resisted in one direction, and the connection is to be automatically broken, and the parts separated, upon imparting any considerable strain from the opposite direction, or where a prompt release of the parts alone is desired.

Accordingly, the device would be adapted for use as a wall socket and terminal connector, when constructed of relatively small dimensions in making the connection for portable lamps, fan-motors and the like.

When employed as a temporary connector for mine-motors, it will be seen that the terminal connector may be immediately slipped into the flanged metal socket-member, so that the pins or extensions *f'* are brought down into engagement with the edges of the ears *c'*, while the nose *f* is yieldingly held between the inner faces of said ears. In this position, the pin-socket slips over its co-acting contact pin, and the terminal connector is retained in place against any normal strain imparted from a direction to the right of the socket; all as will be readily appreciated by making reference to the drawing and particularly to Figs. 2 and 3. The device, of course, will be constructed of sufficiently large size to withstand the somewhat hard usage referred to, and the connections of the positive and negative conductors will be continuously maintained until the respective parts are separated.

When the motor returns from its excursion into any given room or passage, upon passing the connection-socket the terminal connector will first be separated from its contact pin; turning upon the projections *f'* as a pivot (indicated by the arrow, Fig. 2), which projections or pins will be immediately released from the flanged guides *c''*, since the strain will now be in a direction from the left of the connection-socket. Accordingly, it is necessary only for the motor to slow down in order to enable an attendant to slip the terminal connector into place

within the socket, and this part is automatically released when the motor returns and passes the particular connection-socket in use. In this way, not a little time is saved, and the circuit is completed to the motor wherever it may proceed within the mine.

While describing my invention as particularly applied to the mining industry, I wish it to be understood that the same is in no wise confined thereto, but relates to the claimed features below set forth, together with such departures therefrom as may be made by mere skill, and

I accordingly claim as new, and desire to secure by Letters Patent, the following:—

1. In an appliance of the class described, the combination with a connector part adapted to be stationarily mounted, comprising an insulating base, a forwardly positioned metallic contact-part having converging flanged walls, a second insulated contact-part separate and distantly positioned therefrom, and a stop or detent for resisting strain imparted from a given direction, of an associated connector part, comprising an insulating base portion, a forwardly positioned metallic contact having extensions adapted to engage the flanged contact and form a pivot for the connector, and a second insulated contact-part co-acting with the aforesaid insulated contact-part, whereby circuit is maintained through the device while strain is imparted thereto in a given direction, substantially as set forth.

2. In separable electrical connector-members, the combination with one of said members mounting an insulated flanged contact-part, a second connector-member having an insulated contact-part adapted to engage beneath the aforesaid flanged contact-part to form a pivot whereon it may turn, and a stop or detent independent of the contact-parts, for resisting strain imparted from a given direction, whereby circuit is maintained or automatically broken, substantially as set forth.

3. In an electrical connecting device, the combination with an insulating base, a socket-member mounted thereon, comprising converging flanges and upturned ears, a second conductive-member mounted upon said plate at a distance and in a different plane therefrom, and a separable connector-member, comprising a metallic contact adapted to pass between the converging flanges and be engaged by the conductive ears aforesaid, and an additional conductive-part disposed to be conjointly engaged by the second conductive-member above, substantially as set forth.

4. In a device of the class described, the combination with an insulating base plate, two electrical terminals thereon comprising a flanged member, and a fixed pin or stud, of a separable connector-member compris-

ing an insulating body, a forwardly positioned contact having extensions adapted to act as pivots for engaging the flanged member, and a socket for receiving the pin or stud, whereby the parts may readily be connected and disconnected, substantially as set forth.

Signed at Auburn, Illinois, this 7th day of February, 1907, in the presence of two subscribing witnesses.
